CLAIM

The ornamental design for a swivel elbow (partial) male sewer fitting, as shown and described.

DESCRIPTION

FIG. 1 is a right, front top perspective view of a swivel elbow (partial) male sewer fitting embodying our design;

FIG. 2 is a right side elevational view thereof;

FIG. 3 is a left side elevational view thereof;

FIG. 4 is a front side elevational view thereof;

FIG. 5 is a rear side elevational view thereof;

FIG. 6 is a top plan view thereof; and,

FIG. 7 is a bottom plan view thereof.
